(57) **CLAIM**

The ornamental design for a lens plate for optical connector as shown and described.

DESCRIPTION

FIG. 1 is a front, bottom and left-side perspective view of a lens plate for optical connector showing our new design; FIG. 2 is a rear, bottom and left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The evenly-spaced broken lines illustrate portions of the lens plate for optical connector that form no part of the claimed design. The single dot-dash broken lines define the boundary of the claimed design and form no part of the claimed design. The oblique shade lines illustrate a transparent surface.
